UNITED STATES PATENT OFFICE.

DOUGLAS R. HARPER, OF CAMERON, TEXAS.

MOTOR SWITCH.

1,424,901.

Specification of Letters Patent. Patented Aug. 8, 1922.

Application filed April 9, 1921. Serial No. 460,051.

To all whom it may concern:

Be it known that I, DOUGLAS R. HARPER, a citizen of the United States, residing at Cameron, in the county of Milam and State 5 of Texas, have invented certain new and useful Improvements in Motor Switches, of which the following is a specification, reference being had to the accompanying drawings.

10 This invention relates to switches and more particularly to a switch adapted for use in small motors.

An important object of the invention is to provide a motor switch for toy motors 15 and the like which may be very inexpensively manufactured and which may be readily installed upon the motor.

Other objects and advantages of the invention will become apparent throughout 20 the course of the following description.

In the accompanying drawings, wherein for the purpose of illustration is shown a preferred embodiment of my invention and wherein like reference characters designate 25 like parts throughout:

Figure 1 is a side elevation of my switch, the method of connecting the same with the motor being diagrammatically illustrated;

Figure 2 is a longitudinal sectional view 30 taken through the switch;

Figure 3 is a side elevation thereof, and Figure 4 is a plan view thereof.

Referring now more particularly to the drawings, the numeral 10 indicates a suitable support shown in the present instance as comprising a frame plate of one of the small motors sold for operating toys. These plates are usually provided with two pairs of binding posts, one pair of which, 11 and 40 11^a, is connected with the terminals of the field coil of a motor, and the other pair, 12 and 12^a of which is connected with the brushes delivering current to the armature coil.

45 The numeral 13 indicates a switch which comprises a strip of insulating material such as fibre, having an aperture formed therein adapted for the reception of the binding post 11. The strip forming the handle has imbedded therein a conductor 14 extending transversely of the strip and having its ends projecting slightly beyond the sides thereof, and this conductor is adapted to form an electrical contact with the binding post 11 when the switch 13 is rotatably mounted upon the binding post. This may

be accomplished by forming the pivot opening in the conductor 14 and forming openings concentric therewith and of larger size in the switch 13 so that the conductor is 60 exposed for engagement by the binding nut. The strip forming the switch has likewise imbedded therein a second conductor 15 which is insulated from the conductor 14 and electrically connected with a binding 65 post 16 carried by the switch and screw-threaded through the contact. The strip of material forming the switch 13 is provided with an extension 13^a forming an operating handle which coacts with a segment having 70 three stop points.

As illustrated in the drawings, the binding post 11 is disposed intermediate the binding posts 12 and 12^a and the conducting strip 14 is adapted to alternately engage these binding posts to cause an electrical connection between the binding post 11 and the binding posts 12 or 12^a as the case may be. The conductor 15 is likewise adapted to alternately engage these binding posts when the 80 switch is oscillated so as to alternately connect the binding post 16 with the binding posts 12 and 12^a, the conducting strip 15 engaging the binding post 12 when the conducting strip 14 is in engagement with the 85 binding post 12^a, and vice versa. These engagements are made at the extreme throw of the switch and when the switch is in the central position or in the central stop of the 90 segment 17, the insulating portion of the switch which lies between the contacts 14 and 15 is aligned with the binding posts 12 and 12^a and the conductors 14 and 15 are accordingly out of engagement with the binding posts. In use, the binding post 11^a 95 and the binding post 16 are employed for connecting the motor with a source of current. It will be seen that with the switch in the position shown in Figure 1, current will pass through the binding post 16, contact 15, binding post 12 to the coil of the motor field, from the coil of the motor field to the binding post 12^a, through the conductor 14 to the binding post 11, from the binding post 11 to the armature winding, 100 from the armature winding to the binding post 11^a and to the source of current, completing the circuit. When the switch is in the dotted position, the direction of current through the field coil is reversed and current 105 passes from the binding post 16 to the conductor 15, to the binding post 12^a and to the

field coil, returning through the binding post 12, conductor 14, binding post 11, the armature winding, binding post 11^a to the battery or source of current, and the direction of rotation of the armature of the motor is accordingly reversed.

From the foregoing it is believed to be obvious that I have constructed a motor switch for the use with toy motors which 10 may be very cheaply manufactured and very easily applied. It will furthermore be obvious that the construction of the same as hereinbefore set forth is capable of some change and modification without materially departing from the spirit of my invention, and I accordingly do not limit myself to the 15 specific structure hereinbefore set forth except as hereinafter claimed.

What I claim is:

20 1. A reversing switch comprising in combination a support, a pair of contacts mounted upon the support, a third contact likewise mounted upon the support, an insulating member mounted for oscillation 25 upon the last named contact of a conductor carried by said member and electrically connected with said last named contact and adapted to alternately engage the contacts of the pair when the member is oscillated,

a second conductor carried by said member 30 and likewise adapted to alternately engage the contacts of said pair, the engagement of the second conductor with the contacts being alternated with their engagement by the first named conductor.

35 2. A reversing switch comprising in combination a support, a pair of contacts mounted upon the support, a third contact likewise mounted upon the support, an insulating member mounted for oscillation 40 upon the last named contact of a conductor carried by said member and electrically connected with said last named contact and adapted to alternately engage the contacts of the pair when the member is oscillated to the 45 limits of its oscillation, a second conductor carried by said member and likewise adapted to alternately engage the contacts of said pair, the engagement of the second conductor with the contacts being alternated 50 with their engagement by the first named conductor, both of said conductors being out of engagement with said contacts when said member is disposed approximately midway between its limits of swing.

55 In testimony whereof I hereunto affix my signature.

DOUGLAS R. HARPER.
